CLAIM

The ornamental design for portable oxygen concentrating apparatus, as shown and described.

DESCRIPTION

1. Portable oxygen concentrating apparatus

1.1 : Perspective

1.2 : Front

1.3 : Back

1.4 : Left

1.5 : Right

1.6 : Top

1.7 : Bottom

The product indication is a portable oxygen concentrating apparatus; Figure 1.1 is a perspective view of a portable oxygen concentrating apparatus showing our new design; Figure 1.2 is a front view thereof; Figure 1.3 is a back view
